To all whom it may concern:

Be it known that we, William J. Dunn and Robert R. Richolt, citizens of the United States, residing respectively at Winnetka, in the county of Cook and State of Illinois, and Tujunga, in the county of Los Angeles and State of California, have invented a new, original, and ornamental Design for a Child's Toilet Seat, of which the following is a specification, reference being had to the accompanying drawing, forming a part thereof.

Figure 1 is a perspective view of a child's toilet seat showing our new design.

Fig. 2 is a front view of the child's toilet seat shown in Fig. 1.

Figs. 3, 4 and 5 are sectional views taken respectively in the planes of lines 3—3 and 4—4 of Fig. 2 and line 5—5 of Fig. 7.

Fig. 6 is a plan view of the child's toilet seat shown in Fig. 1.

Fig. 7 is a side elevational view of the child's toilet seat shown in Fig. 1.

In accordance with the invention, the seat member, arm rests, and back rests are of transparent plastic material so that grooving on the undersides of the arm rests and on the rear side of the back rest are visible through these members.
